(57) CLAIM

The ornamental design for a bag, as shown and described.

DESCRIPTION

FIG. 1 is a front perspective view of a bag;

FIG. 2 is a front view of a bag;

FIG. 3 is a rear view of a bag;

FIG. 4 is a left side view of a bag;

FIG. 5 is a right side view of a bag;

FIG. 6 is a top view of a bag; and,

FIG. 7 is a bottom view of a bag.

The broken lines illustrate portions of the bag and form no part of the claimed design.
